UNITED STATES PATENT OFFICE.

WILLIAM M. UPP, OF KANSAS CITY, MISSOURI, ASSIGNOR OF ONE-HALF TO ERNEST RUMSEY, OF KANSAS CITY, MISSOURI.

ELECTRIC PRIMER.

1,329,345.

Specification of Letters Patent. Patented Jan. 27, 1920.

Application filed January 31, 1919. Serial No. 274,290.

To all whom it may concern:

Be it known that I, WILLIAM M. UPP, a citizen of the United States, residing at Kansas City, in the county of Jackson and State of Missouri, have invented certain new and useful Improvements in Electric Primers; and I do declare the following to be a full, clear, and exact description of the invention, such as will enable others skilled in the art to which it appertains to make and use the same, reference being had to the accompanying drawings; and to the letters and figures of reference marked thereon, which form a part of this specification.

This invention relates to priming devices for internal combustion engines and it is particularly adapted for use in connection with motor vehicle engines.

The difficulty in starting a "cold" engine is well understood and various attempts have been made to provide means to prime the engine so as to expedite the initial turning over under its own motive power. I have provided means whereby a vaporized explosive fluid may be introduced into the cylinder at a sufficiently high temperature to insure its ignition even when the engine cylinder is cold, and the invention contemplates the provision of means for insuring an accessible supply of motive fluid when there is demand for it as well as to govern the quantity fed into the cylinder at each suction stroke of the piston.

Other objects and advantages as well as the novel details of construction of the preferred form of the invention will be specifically referred to hereinafter, it being understood that changes in form, proportion and minor details of construction may be resorted to without departing from the spirit of the invention or sacrificing any of its advantages.

In the drawings,

Figure I is a diagrammatical view of a manifold, a carbureter and a primer attached in proper relative position with respect thereto.

Fig. II is a vertical, longitudinal, sectional view through the fuel supply chamber, and

Fig. III is a vertical, longitudinal, sectional view through the heater.

Referring now to the drawings by numerals of reference in which corresponding ref-

erence numerals designate corresponding parts through the several views:

1 designates a manifold provided with an intake port 2 connected in the usual manner with an appropriate carbureter 3 supplied from a suitable tank, for example, by gravity, through a supply pipe 4. In the supply pipe 4 I have shown a union 5, to which is connected a pipe or conduit 6 communicating with a fuel supply chamber 7 which communicates with a heater 8 through the medium of a pipe 9, the heater 8 being in communication with the manifold inlet tube through the medium of a pipe 10. The supply chamber 7 is best shown in Fig. II as comprising a cylinder having end walls 11 and 12, the wall 11 being provided with an inlet orifice 13 and the end 12 with an outlet orifice 14. The orifices are provided with conical seats to receive the conical valves 15 and 16 on the stem 17 guided in the spiders 18 and 19, the stem 17 being provided with a collar 20 against which one end of a coil spring 21 bears, the other end bearing against the spider 18 and since the spring 21 has an inherent expansive tendency, the valve 16 will be normally seated to close off the discharge from the chamber 7.

The stem 17 is provided at its upper end with a central orifice 22 adapted to communicate with the chamber 23 in the spool 24 around which the electro-magnetic coil 25 is wound, the coil 25 being adapted to energize the spool and end 11 so as to attract the armature 26 on the stem 17 when the occasion should demand. The electro-magnetic coil is in circuit with a conductor 27 and is in series with a heater element 28 in the heater 8; the heater element and its binding posts 29 being insulated from the heater casing or shell 8. The specific construction of the heater as well as its casing is immaterial, the essential feature being that the fuel may pass from the supply or distributing chamber 7 to the manifold.

Normally the valve 16 will be seated by the action of the spring 21 and inasmuch as the fuel tank will be on a higher level than the casing 7, the fuel will feed through pipe 4 so as to flood the casing 7. When it is desired to prime the engine as, for example, when the engine is cold and it is desired to start the motor vehicle, the operator will

close a switch 30 to complete the circuit 27 which may be energized through any suitable source as, for example, a storage battery 31. As soon as the circuit is closed, the coil 25 will become energized so as to magnetize the end 11 of the casing 7. As soon as this is done, the armature 26 will be attracted and the valve 16 lifted off its seat while the valve 15 will be seated. As soon as the coil 25 is energized, current will pass through the heater 28 to affect it thermally. When the engine is first turned over, either by hand or by a self-starter, the suction stroke of the piston or pistons will draw fuel through the port 14, up through the casing 8, past the heater 28 and into the manifold 2, as indicated in Fig. I. Since the port 22 will be in open communication with the orifice 23 connected to pipe 6, it is obvious that only the amount of fuel can be drawn from the chamber or casing 7 as can be admitted through the port 22. Therefore, the charge admitted to the cylinder will be measured by the size of the orifice 22 and as it passes through pipe 9 on its way through chamber 8, the heater 28 will raise its temperature to the vaporizing point so that it will be admitted into the manifold with a sufficiently high thermal value to insure its ignition when it enters the cylinder. Of course, as soon as the explosions are taking place with normal regularity, the switch will be opened to break the circuit and the carburetor 3 will supply the fuel.

Such a device as just described will be both efficient and economical in construction, the cost of manufacture being reduced to a minimum. For example, an important detail of construction is the construction of the spool 24 so that one end may constitute a plug for the cylinder 7, constituting the casing of the fuel supply device, the end of the spool being conically recessed to make a valve seat. This makes a very simple and effective supply mechanism, the construction being such that no pumps or ejectors are used, sufficient fuel being provided by the suction stroke of the piston. During the priming operation, the fuel fed to the engine will be bi-passed around the carburetor but after the engine has been brought up to speed, the primer will be cut

out and the carburetor will operate in the usual way, it being apparent that any carbureting system may be employed.

From the foregoing, it will be seen that an inexpensive, durable and efficient device of the character described has been provided for priming engines and particularly motor vehicle engines and that the device may be conveniently operated to enable the driver to effect the priming without getting out of the car.

What I claim and desire to secure by Letters Patent is:

1. A priming device for internal combustion engines, comprising a fuel supply chamber having an ingress port and an egress port, a valve stem within said chamber having a central inlet orifice extending through one end, valves on the stem to alternately open and close the respective ports, a heater casing in communication with said chamber, and means for connecting the chamber to the manifold of an engine.

2. A priming device for internal combustion engines, comprising a fuel supply chamber having an ingress port and an egress port, a valve stem within said chamber having a central orifice extending through one end and discharging into the fuel supply chamber, valves rigidly connected to said stem, one of said valves being positioned above the discharge end of the orifice, a heater associated with the chamber, and means for connecting the heater with the manifold of an engine.

3. A priming device for internal combustion engines, comprising a fuel supply chamber having an ingress port and an egress port, a valve stem in the chamber, valves rigid on said stem and movable to alternately open and close the respective ports, a pipe leading from the egress end of the casing a heater casing connected to the pipe, a heating element therein, a pipe connecting the heater to the engine manifold, an electro-magnet closing the top of the fuel supply chamber and having a valve seat for the inlet valve, an armature on the valve stem, and means for simultaneously energizing the electro-magnet and the heating element in the heater casing.

In testimony whereof I affix my signature.

WILLIAM M. UPP.
